(57) **CLAIM**

The ornamental design for a shoe sole, as shown and described.

DESCRIPTION

FIG. 1 is a perspective view of a shoe sole embodying my new design;

FIG. 2 is a front view thereof;

FIG. 3 is a rear view thereof;

FIG. 4 is a right side view thereof;

FIG. 5 is a left side view thereof;

FIG. 6 is a bottom plan view of the shoe sole of FIG. 1; and, FIG. 7 is a top plan view of the shoe sole of FIG. 1.

The broken line immediately adjacent to the solid lines in FIG. 7 represents the boundary of the design. Neither the broken line nor the area within forms any part of the claim.
